UNITED STATES PATENT OFFICE

107,483

DESIGN FOR A COMBINATION SHIRT AND SHORTS

Everest D. Haight, New York, N. Y., assignor to E-Z Mills, Inc., New York, N. Y., a corporation

Application October 5, 1936, Serial No. 65,168

Term of patent 3½ years

To all whom it may concern:

Be it known that I, Everest D. Haight, a citizen of the United States, residing at New York, in the county and State of New York, have invented a new, original, and ornamental Design for a Combination Shirt and Shorts, of which the following is a specification, reference being had to the accompanying drawings, forming part thereof, wherein:

Fig. 2 is a rear elevation of a combination shirt and shorts embodying the design, with part broken away for illustrative purposes.

My design comprises the combination shirt and shorts shown having folds at the sides and an outwardly disposed panel beginning from the folds, adjacent the waistline and depending to a point approximately half the length of the shorts on the back section, as shown.

I claim:

The ornamental design for a combination shirt and shorts substantially as shown and described.

EVEREST D. HAIGHT.
